ADDRESS PLATE

Elmer F. Richter, Cleveland Heights, Ohio, assignor to Addressograph-Multigraph Corporation, Cleveland, Ohio, a corporation of Ohio

Application November 6, 1940, Serial No. 364,523

5 Claims. (Cl. 101—369)

This invention relates to an address plate comprising a frame carrying an embossed printing plate and also preferably an index card. The plate and card while held in place in use are readily removable to allow substitution whenever the legends they carry—for instance, a name and address—are to be changed.

A general object of the invention is to provide a frame which may be very cheaply constructed and which, while being light in weight, is of sufficient rigidity and strength to prevent distortion in the use.

More particularly, my address plate is concerned with the frame especially useful in machines where the address plate travels lengthwise thereof, either in coming from its magazine to printing position or passing from one printing position to another for successive imprints or into the receiving magazine at the end of the operation.

Address plates are usually of oblong form, the printing plate and card each having a length several times the width. Heretofore, it being customary to form transverse guiding ribs on the under-side of the plate at its ends. Such ribs form very efficient skid rails when the plate is shifted transversely to the frame but have to be dragged crosswise on the support when the plate is shifted lengthwise. As the lengthwise shifting is of much greater extent in many machines than the crosswise movement, I have devised a frame which has ribs running lengthwise thereof forming more efficient skid rails for the greater portion of the travel.

In my invention I form the guiding ribs along the longitudinal edges of the plate, which may be conveniently referred to as its top and bottom, since that is the position the plate occupies in the storage drawer. Heretofore, it has been customary to curl over above the front of the plate the upper and lower edges to provide holding devices for the top edge of the card and the bottom edge of the printing plate. In my invention I bend the top and bottom edges onto the rear of the plate to form the reinforcing and guiding ribs and I provide upset lips facing toward an intermediate region of the frame to engage the lower edge of the printing plate and the upper edge of the index card. Such lips are cut out of the material of the frame but by reason of the reinforcing action of the adjacent guiding ribs do not interfere with the stiffness of the frame.

At its ends I turn over the extreme end portion of the material to form a hem or snug reinforce, which while sufficient to stiffen the plate

at the ends does not project to the extent of the longitudinal ribs and hence in no matter interferes with the free longitudinal sliding of the frame in use.

My improved invention is illustrated in the drawing hereof and is hereinafter more fully described and its essential novel features are summarized in the claims.

In the drawing, Fig. 1 is a front view of my address plate, with the printing plate and the index card partly broken away; Fig. 2 is an edge view of the frame; Fig. 3 is a back view of the frame; Fig. 4 is a cross section on double scale of the address plate, as indicated by the line 4—4 on Fig. 1; Fig. 5 is a fragmentary section also on double scale through an end portion of the frame and printing plate, as indicated by the line 5—5 on Fig. 1; and Fig. 6 is a perspective of a portion of the frame, adjacent a lower corner.

20 In the drawing, 10 indicates the frame, 20 the printing plate and 30 the index card, these three members together being conveniently denominated an "address plate."

25 The frame is made of a single sheet of thin comparatively light metal. Its upper and lower edges are bent toward the rear and thence backwardly over the panel portion of the plate for a short distance, thence outwardly in a trough-like form and finally terminates in a short flanged portion engaging the back of the panel portion, all as indicated at 11 in Figs. 2, 3, 4 and 6.

30 The hollow ribs 11 terminate short of the ends of the face panel a short distance, as shown in Fig. 3. The ends of the panel are flanged over 35 onto the back side thereof by a hem or tight bend which fits against the back of the plate, as indicated at 12 in Figs. 3, 5 and 6. This reinforcing hem extends for the full width of the plate across the ends of the ribs 11, substantially engaging 40 with such ends, as shown in Fig. 3.

35 The printing plate 20, which in use is provided with embossed printing characters 21 (Figs. 1 and 4), is mounted on the front face of the frame 10 being slid lengthwise into place beneath 45 upwardly overhanging lips 14 near the lower edge of the frame and downwardly overhanging intermediately located lips 15. The index card 30 is held at its upper edge beneath downwardly overhanging lips 16 and at its lower edge beneath 50 upwardly overhanging lips 17. All of these lips are cut from the body of the frame and pressed first forwardly and then parallel with the front of the frame to overhang the plate or card as the case may be, as illustrated in Fig. 4.

55 The lips 14 and 16 may very conveniently be of

considerable length, as illustrated, to hold the plate and card snugly against the frame substantially throughout the length and not allow the possibility of either the plate or card being bowed outwardly between lips sufficiently to permit anything to get behind such plate or card. These comparatively long cut-outs to make these lips might weaken the plate sufficiently so that it would be bent in use adjacent the edge were it not for the reinforcing ribs 11 extending along such edges.

I also prefer to make the intermediately located lips 15, which engage the printing plate, of considerable length. However, as to the card, it is not so important to have long lips at the lower edge of the card, as there is less danger of anything being inadvertently tucked in behind the card in that region. Accordingly, in this instance I prefer to use short lips 17 so as not to materially weaken the frame in the intermediate region. I provide also a stamped up corner pocket 18 to engage one corner of the card and a stamped up abutment 19 to engage the opposite end. The card, which is ordinarily of paper, is put into place beneath the various lips by bowing it slightly and then flattening it.

The printing plate, which is retained at its edges by the lips 14 and 15, is retained at one or both ends by springs tongues 40 which are cut out of the material of the frame and have suitable abutments to engage the printing plate. Preferably, these tongues have raised platform portions 41 connected with the tongue proper by simple brace 42 and by edge braces 43 (Fig. 6) after the manner of Patent No. 2,030,865 of W. T. Gollwitzer. The spring tongues 40 are normally in the plane of the frame panel 10 and the intermediate connections 42 occupy notches 22 in the plate.

To remove the plate, the operator engages the platform 41 with his thumb or finger and presses it down level with the face of the panel, and then slides the plate out over the depressed platform. In mounting the plate on the frame, the edge of the plate is placed over the platform and manual pressure against the plate depresses the platform so that the plate may slide into place beneath the lips 14 and 15, after which the tongue 40 springs back into place bringing the platform opposite the end of the plate with the abrupt shoulder of the platform engaging the end of the plate on opposite sides of its notch, while the central brace 42 occupies the notch of the plate.

By providing the spring tongues with a raised platform as described, at each end of the frame, as illustrated in Figs. 1 and 3, I can shove the plate into place from either end of the frame or remove it from either end as may be most convenient. If it is desired, however, the spring tongue need be provided only at one end, for instance, the right hand end of the plate and a fixed abutment used at the other end, as illustrated for instance in Patent No. 2,115,444 of W. T. Gollwitzer.

It will be seen from the drawing and the description given that my frame is well adapted for carrying the printing plate and index card, effectively holding them in place in use while allowing their ready removal whenever desired.

It will also be noticed that the flanging of the longitudinal ribs 11 and the transverse bends 12 are all in the same direction onto the rear side

of the frame. This makes a cheaper operation than where the ribs are on one side and the edges are curled over onto the other face in a position spaced from the panel to act as retainers for the printing plate and card, as formerly. The longitudinal ribs at the top and bottom and the transverse bends at the edges reinforce the plate so that it will not be bent out of its plane during using. By making the ribs longitudinal, I utilize such ribs for the double purpose of providing effective skid rails for longitudinal movement of the plate, and for stiffening the plate adjacent the comparatively long cut out portions which provide the retaining lips.

I claim:

1. An address plate comprising an oblong frame having ribs on its rear face adjacent the top and bottom edges, said ribs being formed by bending over the edge portion of the front panel of the frame to provide hollow trough-like portions at the rear, and overhanging lips cut out from the panel of the plate adjacent the ribs, and a printing plate and an index card mounted on the frame and over-lapped by such lips respectively.

2. A frame for an address plate comprising a panel of metal having its top and bottom margins bent over onto the back face in trough-like form to provide hollow longitudinal ribs, there being incisions in the plate extending longitudinally adjacent the ribs and lips caused by said incisions and comprising portions of the plate which are bent upwardly and then substantially parallel with the plate in the direction away from the ribs, said lips accordingly overhanging the intermediate portion of the plate.

3. A frame for an address plate comprising a substantially flat panel of oblong form having its top and bottom margins bent over onto the rear side of the panel to form longitudinal ribs, the ends of the panel being bent over onto the rear side to form reinforces, and raised lips cut out of the panel and overhanging the face thereof.

4. A frame for an address plate comprising a substantially flat panel of metal of oblong form having its top and bottom margins bent over onto the rear side of the panel into the form of hollow longitudinal ribs, the ends of the panel being bent over onto the rear side in the form of snug hems, and raised lips cut out of the panel adjacent the ribs and overhanging the face of the panel.

5. A frame for an address plate comprising a panel of sheet metal of oblong form with the upper and lower margins of the panel being bent over onto the back face of the panel to provide hollow longitudinal ribs and the end portions of the panel bent over onto the rear face to provide reinforces, there being lips cut out from the metal of the panel by incisions adjacent the longitudinal ribs, said lips remaining attached to the panel near the ribs and extending from the plane of the panel end thence toward each other over the face of the panel, and two rows of intermediate lips cut out of the panel and facing in opposite direction, one row cooperating with the lips adjacent the lower edge of the frame to retain a printing plate, the other row cooperating with the lips adjacent the upper edge of the frame to retain an index card, and means on the frame including a spring tongue to engage the ends of the printing plate.

ELMER F. RICHTER.
